United States Patent Office

Des. 226,576
Patented Mar. 27, 1973

226,576

CONTAINER CLOSURE OR THE LIKE

James B. Swett, Barrington, and Jack V. Croyle, Woonsocket, R.I., assignors to Dart Industries Inc., Los Angeles, Calif.

Filed Mar. 9, 1971, Ser. No. 122,641

Term of patent 14 years

Int. Cl. D7—02

U.S. Cl. D44—1 B

FIG. 1

FIG. 2

FIG. 3

FIG. 1 is a perspective view of a container closure showing our new design;

FIG. 2 is a side elevational view thereof; and,

FIG. 3 is a bottom view thereof.

We claim:

The ornamental design for a container closure or the like, substantially as shown.
